Primary Examiner — Elizabeth A. Albert

(57) **CLAIM**

The ornamental design for a water brush pen, as shown and described.

DESCRIPTION

FIG. 1 is a perspective view of a water brush pen showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the water brush pen where a pen cover is connected with a pen body; and,

FIG. 10 is an enlarged view of portion 10 shown in FIG. 1. The broken lines in the drawings depict portions of the water brush pen that form no part of the claimed design.

1 Claim, 10 Drawing Sheets
